ANTENNA WHIP SPRING BASE

Charles W. McVey, North Madison, Ohio, assignor to
Anzac Industries, Inc., a corporation of Ohio

Filed Nov. 14, 1966, Ser. No. 4,652

Term of patent 14 years

(Cl. D14—6)

FIG.2

FIG.1

FIG.3

FIG. 1 is a side elevation taken from slightly above, showing an antenna whip spring base incorporating my new design with an antenna whip shown in phantom; FIG. 2 is a top plan of the antenna whip spring base shown in FIG. 1; and

FIG. 3 is a bottom view of the antenna whip spring base shown in FIG. 1.

The portions shown in phantom in the drawings are included for completeness of a showing of the antenna whip spring base but form no portion of my new design.

I claim:

The ornamental design for an antenna whip spring base, as shown and described.
